WIRE-DRAWING MACHINE

Albert G. Blodgett, Worcester, Mass., assignor to
 Morgan Construction Company, Worcester,
 Mass., a corporation of Massachusetts

Application December 8, 1939, Serial No. 308,223

3 Claims. (Cl. 205—14)

This invention relates to wire-drawing machines, and more particularly to machines of the type having a series of dies through which the wire is drawn by means of rotating drums or blocks to effect successive reductions of the wire.

It has been recognized heretofore that certain advantages arise from the maintenance of an appreciable tension in the wire between each drum and the succeeding die. This so-called "back tension" not only decreases the power required to drive the machine, but it also prolongs the life of the dies by reducing the die friction and the resultant heat, and makes it possible to draw wire at higher speeds. While attempts have been made to construct machines which would operate in this manner, the prior machines have in general been complicated, expensive, unreliable, and difficult to maintain in proper adjustment.

It is accordingly one object of the invention to provide a simple, inexpensive and reliable wire-drawing machine of the type having rotatable drums to draw wire through a series of dies successively, the various parts being so constructed and arranged as to permit an accurate control of the back tension in the wire.

It is a further object of the invention to provide a wire-drawing machine having a plurality of rotatable drums, together with a simple and reliable mechanism for rotating the drums and applying a predetermined and readily adjustable torque to each of the drums.

It is a further object of the invention to provide a novel construction for a multiple die wire-drawing machine which is so arranged that the wire will neither slip on the drums nor continuously accumulate thereon during the operation of the machine.

With these and other objects in view, as will be apparent to those skilled in the art, the invention resides in the combination of parts set forth in the specification and covered by the claims appended hereto.

Referring to the drawing illustrating one embodiment of the invention, and in which like reference numerals indicate like parts,

Fig. 1 is a somewhat diagrammatic view of a wire-drawing machine; and

Fig. 2 is an enlarged section taken on the line 2—2 of Fig. 1.

The embodiment illustrated comprises a series of rotatable wire-drawing drums or blocks 10, 11 and 12 with which there are respectively associated a series of dies 14, 15 and 16. The

drum 10 draws the wire through the first die 14, the wire then passing through the die 15 to the drum 11 and thence through the die 16 to the drum 12, which serves as a finishing drum. The drum 10 is driven by a motor 18 which is connected to the drum by means of suitable gearing 19. Similarly, the drum 11 is driven by a motor 20 through the medium of gearing 21. The finishing drum 12 is driven by a motor 23 which is connected to the drum by means of gearing 24. The rate at which the wire passes through the machine is determined by the speed of the finishing drum 12, which in turn is determined by the speed of the motor 23. This motor may be an electric motor, and it is preferably of the adjustable speed type so that the rate of wire drawing may be controlled.

The motors 18 and 20 are hydraulic motors of the constant displacement type. One suitable and well-known construction therefor is shown in Fig. 2 and comprises a pair of intermeshing gears 26—26 which are forced to rotate by the pressure of the hydraulic fluid passing through the motor. A suitable fluid, such as oil, is supplied for the operation of the motors 18 and 20 through pipes 27 and 28 respectively from a pressure-producing source, such as a pump 30 driven by an electric motor 31. This pump may be of any suitable and well-known construction, and it may be supplied with oil through an inlet pipe 32 which communicates with a reservoir or tank 34. Pipes 35 serve to return the exhaust fluid from the motors to the reservoir. Means is preferably provided to control the pressure of the oil delivered by the pump, and for this purpose a by-pass 37 and relief valve 38 are provided between the pump outlet and the exhaust. One suitable construction for the relief valve 38 is disclosed in the patent to Terry, No. 1,863,075.

Means is provided to regulate automatically the pressure of the oil supplied to the respective motors 18 and 20, thereby controlling the torque which these motors will apply to the wire-drawing drums. For this purpose a pressure reducing and regulating valve 40 is arranged to control the flow through the pipe 27, and a similar valve 41 is arranged to control the flow through the pipe 28. Each of the valves 40 and 41 is provided with a handwheel 42 for the purpose of adjustment. These valves may be of any well-known type adapted to maintain a substantially constant predetermined delivery pressure, one suitable construction being disclosed in the patent to Temple, No. Re. 19,545. For convenience in adjustment, pressure gauges 43 are connected to the

pipes 27 and 28 to indicate the fluid pressure at the inlets of the respective hydraulic motors 18 and 20.

It will now be understood that with the apparatus as so far described each of the motors 18 and 20 will be supplied with operating fluid at a substantially constant pressure, which may be predetermined by the adjustment of the hand-wheels 42. Consequently the torque applied to the respective drums 10 and 11 will be predetermined and substantially constant, since the motors are of the constant displacement type. By proper selection of the applied torque it is possible to maintain a predetermined back tension in the wire immediately anterior to the dies 15 and 16. The speeds of the drums 10 and 11 will be determined by the speed of the finishing drum 12 and by the amount of reduction effected by the dies, so long as the wire extends throughout the entire machine. During the threading up of the machine, or during the run out of the tail end of the wire, or in case the wire breaks, the situation will be different. Under such circumstances there will be one of the hydraulically driven drums which is not pulling wire through a die, and as a result the corresponding hydraulic motor will take all the oil delivered by the pump 30. Consequently the unloaded drum will operate at high speed, and the remaining hydraulically driven drum or drums will not operate at all.

In order to overcome this difficulty I provide means whereby the flow of pressure fluid through each hydraulic motor is prevented unless the corresponding block is maintaining a tension in the wire anterior thereto. For this purpose, as shown in Fig. 1, a valve 45 is provided in the pipe 27, this valve being operated by a solenoid 46, the construction being such that the valve will open when the solenoid is energized and close when the solenoid is de-energized. The solenoid is connected to a suitable electrical source 47 through a switch 49 which is biased toward open position by a spring 50. This switch is shunted by a normally-open push button 51. Means is provided to close the switch 49 when the drum 10 is drawing wire through the die 14, and for this purpose the die is slidably mounted on a support 53 and connected to the switch by means of a lever 54 fulcrummed on a pin 55. A similar construction is provided in connection with the second die 15 and the second block 11, the pipe 28 having a valve 57 therein which is operated by a solenoid 58 so arranged that the valve will open when the solenoid is energized and close when the solenoid is de-energized. The solenoid 58 is connected to a source 59 of electricity through a switch 61 which is biased toward open position by a spring 62 and shunted by a normally-open push button 63. The die 15 is slidably on a support 65 and connected to the switch 61 by means of a lever 66 fulcrummed on a pin 67.

The operation of the invention will now be apparent from the above disclosure. With the motor 31 running and no wire passing through the machine, the switches 49 and 61 will be held open by their respective springs 50 and 62, the solenoids 46 and 58 will be de-energized, and the valves 45 and 57 will be closed. Hence no fluid will flow through the motors 18 and 20, and the blocks 10 and 11 will be stationary. To thread the machine, the operator will point the end of the wire, pass it through the first die 14 and attach it by a suitable grip to the drum 10 in a well-known manner. He will then close the push

button 51, which will energize the solenoid 46 and open the valve 45, admitting fluid to the motor 18. This will rotate the drum 10, and draw the wire through the die 14, which will slide along its support 53 until the switch 49 is closed, so that the operator may release the push button without de-energizing the solenoid. When a sufficient number of wraps of wire have been formed about the drum 10, the operator will stop the machine by stopping the electric motor 31. He will then re-point the wire, pass it through the second die 15, and attach it by a suitable grip to the second drum 11. Then by starting the motor 31 and closing the push button 63 momentarily, he can draw the wire through the die 15. In case the wire slackens sufficiently to allow rearward movement of the first die 14, it may be necessary to close the push button 51 also. When the desired number of wraps have been formed about the drum 11, the motor 31 will be stopped, and the wire will be re-pointed, passed through the die 16, and attached by a grip to the finishing drum 12. By starting both the motors 31 and 23, and if necessary closing the push button 63 momentarily, several turns of wire may be formed about the drum 12. The machine will then be stopped and the grip removed. This completes the threading of the machine. The operator will now decrease the pressure at the delivery side of the automatic valves 40 and 41 to predetermined values by turning their respective handwheels 42, whereupon he will start the electric motors 31 and 23. The machine will proceed to draw wire through the several dies, with a predetermined back tension in the wire anterior to each of the dies 15 and 16, the speed of the wire being controlled by the speed of the motor 23. There will be no accumulation of wire except on the finishing drum, and no slipping between the wire and the drums. The hydraulic motors operate with predetermined fluid pressures and a constant displacement, and hence will transmit predetermined torques to their respective drums. As the tail end of the wire passes through the first die 14, all load will be removed from the first drum 10 and its driving motor 18. The spring 50 will immediately open the switch 49, de-energizing the solenoid 46 and closing the valve 45. This will prevent fluid from entering the motor 18, so that this motor will stop, instead of accelerating to a high speed (as would otherwise occur), and full fluid pressure will be maintained for operation of the motor 20. The wire will loosen about the drum 10 and will be withdrawn therefrom by the continued rotation of the drum 11. As the tail end of the wire passes the die 15, the spring 62 will open the switch 61, de-energizing the solenoid 58 and closing the valve 57. This will stop the drum 11, and the wire will be withdrawn therefrom by the continued rotation of the finishing drum 12. The motor 23 will then be stopped, the finished wire will be removed from the drum 12, and the machine will be re-threaded as before.

In further explanation as to why there will be a predetermined back tension, it will be noted that the tension between the first die 14 and the first drum 10 is constant, since it is a function of the amount of reduction and the composition of the wire, factors which remain substantially uniform in the commercial drawing of wire. The tangential force applied to the wire by the drum 10 is predetermined, since the motor 18 has a constant displacement and is supplied with fluid

at a predetermined pressure. It necessarily follows that the back tension between the drum 10 and the second die 15 will be predetermined, since it is equal to the difference between the constant tension anterior to the drum and the predetermined force applied to the wire by the drum. Similarly, the tension between the die 15 and the drum 11 will be predetermined, since it is the sum of the predetermined back tension anterior to the die 15 and the constant reactive force of the die. Since the drum 11 applies a predetermined force to the wire, it necessarily follows that the back tension between this drum and the following die 16 is predetermined, this back tension being equal to the difference between two predetermined forces. In this connection it will of course be recognized that under all normal conditions, with the drums neither accelerating or decelerating, the tangential forces on the drums are in equilibrium.

It will now be apparent that the invention provides a dependable multiple-die machine of a comparatively simple and inexpensive construction adapted to draw wire with a predetermined back tension and without slipping of the wire on the drums. The pressure reducing and regulating valves 40 and 41 are of a standard construction which can be obtained commercially at comparatively low cost. The hydraulic motors 18 and 20 are relatively inexpensive, since they are of the constant displacement type which requires no complicated adjusting mechanism.

Having thus described my invention, what I claim as new and desire to secure by Letters Patent is:

5 1. A wire-drawing machine comprising a plurality of dies, a plurality of rotatable drums to draw wire through the dies successively, means to drive one of the drums at a predetermined speed, a plurality of constant displacement hydraulic motors each of which is connected to another of the drums to drive the same, and means to supply fluid to each of the motors at an independently adjustable predetermined pressure.

10 2. A wire-drawing machine comprising a plurality of dies, a plurality of rotatable drums to draw wire through the dies successively, means to drive one of the drums at a predetermined speed, a plurality of constant displacement hydraulic motors each of which is connected to another of the drums to drive the same, means to supply operating fluid to the motors, and a separate pressure reducing and regulating valve associated with each motor to control the pressure of the operating fluid supplied thereto.

15 3. A wire-drawing machine comprising a plurality of dies, a plurality of rotatable drums to draw wire through the dies successively, means to drive one of the drums at a predetermined speed, a plurality of constant displacement hydraulic motors each of which is connected to another of the drums to drive the same, means providing a supply of operating fluid, pipes connecting the fluid supply means with the respective hydraulic motors, and a separate pressure reducing and regulating valve in each pipe to control independently the pressure of the fluid delivered to the corresponding motor.

ALBERT G. BLODGETT.
